UNITED STATES PATENT OFFICE.

LOUIS LAFOND, OF ST. ETIENNE, FRANCE.

LOOM FOR WEAVING DOUBLE-PILE FABRICS.

Application filed September 5, 1923, Serial No. 661,056, and in France February 27, 1923.

The present invention relates to devices for making figured jacquard velvet in one or more colours in double pile velvet ribbon looms weaving several pieces at once and also in double pile velvet fabric looms.

The accompanying drawing shows an embodiment of a loom mechanism according to the invention.

Figs. 1 and 1^a, read together, are a transverse sectional elevation of the loom and its frame.

Fig. 2 is an elevation of the rear face of the loom.

Fig. 3 is a section on the line 3—3 of Fig. 2.

Fig. 4 is a plan view of the gripping device fixed to the rear part of the loom.

Fig. 5 is a section on the line 5—5 of Fig. 1 showing the arrangement of bobbins.

Fig. 6 is a plan view thereof from above.

Fig. 7 is a plan view of the lower hole board through which the threads from the bobbins pass.

Fig. 8 is a perspective view showing the members which connect the two sides of the framework and the tension weights for the threads as they pass from the bobbins to the pile feeding device.

Creel.—The creel carrying the set of bobbins consists of a wooden bar 1 on which are fixed spindles 2 to receive bobbins 3. Fig. 5 shows an embodiment of a set comprising two spindles with their bobbins, an empty spindle and a small spindle for holding the spring which acts upon the next adjacent bobbin for a purpose to be later set forth.

The number of bobbins may vary both in the length and in the breadth of the creel, according to the dimensions of the fabric to be manufactured.

At the base of each spindle there is a helical spring 4, the lower branch 4' of which bears against the coils of the spring on the next succeeding spindle, while the upper branch 4'' bears against the next adjacent bobbin or against the next adjacent spindle itself when it carries no bobbin.

The threads from the bobbins which are maintained under tension by the springs 4 are directed towards the lower part of the bar 1 where they traverse guides formed in a lower hole board 5 which is fixed in an inclined position at the end of said bar.

On leaving the guide board, the threads

pass through the eyes of tension weights 6 (see Fig. 8) and are then directed towards the pile feeding device.

A transverse member 7, which connects the two sides of the framework, prevents the tension weights from being carried forward with the threads.

Pile feeding device.—The pile feeding device consists of two cast-iron supports 8, 8, each secured by means of a bolt 9 to a cross piece 10 at the rear of the loom. The ends of the upper fixed member of a gripping device 12 are also fixed by bolts 11 to the upper part of the supports 8. A rubber band 13 is fitted in a groove extending throughout the length of the lower edge of the upper member 12 of the gripping device.

Below the fixed upper member 12 of the gripping device there is a movable member 14. The members 12 and 14 act like a vice to hold the threads. The ends of the movable member 14 extend into grooves formed on the inner faces of the supports 8 which thus serve as guides for said member. On the upper edge of the movable member 14 there is a wooden covering 15 secured by screws. A band of cloth 16, coated with pulverised glass or emery, is glued to the covering 15 to ensure the adhesion of the threads when upper member 12 and the lower member 14 of the gripping device are brought together. At one of the upper corners and extending the full length, of the wooden covering 15 is a recess into which is fixed a round iron or brass rod 17 projecting slightly above the level of the upper edge of said covering, in order to prevent the pile threads resting on the clamp band 16 from being frayed during the upward movement of the movable member 14 of the gripping device.

On the driving shaft 18 are mounted two cams 19, 19 secured by set screws. These cams act on levers 20, fixed on a shaft 21 to which is imparted an oscillatory movement in order to reciprocate rods 22, 22, 100 mounted at the end of the levers 20.

At the upper end of each of the rods 22 is mounted a connecting member 23, of which members 23 the upper ends have screw threaded connection with the lower part of the member 14, thus providing for regulation of pressure exerted by the member 14 against the rubber band 13 of the fixed member 12.

The driving shaft 18 at one end outside 110

the frame also carries a sprocket wheel 24 which transmits its movement of a chain to another sprocket wheel 25 secured to one end of a shaft 26 which actuates a presser bar 28. On this shaft 26 are fixed two arms 27, the ends of which support the bar 28. By this arrangement the shaft 26 is rotated and transmits its rotation to the bar 28.

Mode of action.—When the pile thread reaches the extreme point 29 of its travel, the cam 19, by means of the lever 20 and of the rod 22, forces the member 14 against the rubber band 13 of the member 12. The pile warp being thus clamped, the presser bar 28, which turns in the direction shown by the arrow (Fig. 1), bears on the pile warp which is stretched and consequently causes the tension weights 6 to rise. The unwinding of the pile threads from bobbins 3, which is effected at the same time gives the necessary further length of thread required by the warp during weaving. Consequently, during the succeeding rise of the pile thread after it has arrived at its extreme point 29, the weight 6 alone ensures its tension. Then, during the whole simultaneous action of the gripping device and of the bar 28, the pile thread remains raised until members 12 and 14 of the gripping device move apart. The pile thread being thus liberated descends again to its starting point and is kept taut by the tension weight 6.

From the foregoing it will be understood that the pile feeding device constitutes a complementary and indispensable part of the creel. In fact, this device obviates any regulation of the bobbin springs which might cause irregularity in the tension of the pile threads and, consequently, irregularity in the depth of pile.

The table 30, of the type generally used in velvet looms, has an opening 31 of a length substantially the same as the width of the fabric to be manufactured.

Beneath the table 30 is mounted a roller 32 the ends of which are journalled in supports 33 secured to the under side of the table 30.

The fabric 34 after it is woven passes first over the table 30 in front of the batten, then into the opening 31; it then descends, passing round the roller 32, and ascends through the opening 31 whence it passes to be cut by the knife 35.

The pile threads hanging below the under side of the fabric, and which are cut by the knife, cannot unravel during the weaving because they are clamped at the angles of the opening 31 by the tension of

the fabric, and the loom consequently is capable of weaving designs of great length.

This mechanism, moreover, has the advantage of eliminating the recoil of the piece, which recoil is usually produced by the batten and consequently makes it possible to obtain a better cut.

Having thus described the nature of the said invention and the best means I know of carrying the same into practical effect, I claim:

1. In a loom for weaving double pile fabric embodying a creel from which the warp threads to form the fabric are drawn and heddles, means for gripping the threads at the end of each movement thereof to the heddles, said gripping means comprising a fixed member and a movable member between which the threads pass to the heddles, and a rotatable cam for moving said movable member toward said fixed member.

2. In a loom for weaving double pile fabric embodying a creel from which the warp threads to form the fabric are drawn and heddles, means for gripping the threads at the end of each movement thereof to the heddles, said gripping means comprising a pair of relatively movable members between which the threads pass on their way to the heddles, one of said gripping members being provided on its working face with a fabric covering having hard particles embedded therein, a rotatable shaft, and cams carried by said shaft for actuating said gripping means.

3. A gripping means according to claim 2, wherein a bar of substantially round cross section is secured to one corner of the working face of the fixed gripping member.

4. In a loom for weaving double pile fabric embodying a creel from which the warp threads to form the fabric are drawn and heddles, means for gripping the threads at the end of each movement thereof to the heddles, said gripping means comprising a pair of relatively movable members between which the threads pass on their way to the heddles, a rotatable shaft, cams carried by said shaft for actuating said gripping means, and a presser bar associated with said gripping means for applying tension to the threads when clamped between said gripping members, said presser bar being actuated from said rotatable shaft in timed relation to the movement of the gripping members.

In testimony whereof I have signed my name to this specification.

LOUIS LAFOND. [L. S.]
